UNITED STATES PATENT OFFICE.

LITFALLAH G. SABBAG, OF BOSTON, MASSACHUSETTS, ASSIGNOR OF ONE-HALF TO
MAURICE A. METCALF, OF BOSTON, MASSACHUSETTS.

FASTENER-ATTACHING MECHANISM.

Application filed May 28, 1920, Serial No. 384,875. Renewed October 30, 1924.

To all whom it may concern:

Be it known that I, LITFALLAH G. SABBAG, a citizen of the United States of America, and resident of Boston, in the county of 5 Suffolk and State of Massachusetts, have invented new and useful Improvements in Fastener-Attaching Mechanisms, of which the following is a specification.

This invention relates to improvements 10 in fastener attaching mechanisms and more particularly to machines for sewing on buttons, although in certain of its aspects it is not limited to the type of fastener employed.

Button sewing attachments for sewing 15 machines have long been known and in connection with the employment of such devices there has been some attempt to provide for automatically feeding the buttons into attaching position.

Such arrangements, however, so far as 20 known, have been found objectionable from the standpoint of utility and economy by reason of their failure to present successive buttons with certainty and regularity in 25 position for the proper passage of the securing instrumentalities through the button eye, or by reason of the complexity and delicacy of the parts employed, rendering them expensive to make and difficult to maintain 30 in proper operative condition.

The object of the present invention is to provide in a simple and reliable manner for the feeding of buttons successively from a suitable reservoir or supply into proper position with relation to the attaching instrumentalities of the sewing machine to permit 35 the certain operation of the latter.

To this end the invention contemplates first 40 the provision of a removable button reservoir which may be of interchangeable construction so that a supply of filled reservoirs may be kept on hand for successive use, such reservoirs being preferably so designed that buttons held thereby are automatically oriented into proper position for 45 attachment; secondly, button transferring means which shall operate with certainty to convey the properly oriented button from the reservoir to button clamping means of 50 any usual construction associated with the stitch forming mechanism, and lastly, suitable connections for operating the various parts of the mechanism of a simple and dur-

able character and which will require little attention and few repairs under ordinary 55 use.

In carrying into effect the object stated a button reservoir and transferring means have been designed of exceedingly simple 60 form and durable construction and which, by means of suitable controlling elements, may be caused to function with speed and accuracy.

While it is contemplated that the object 65 of the present invention may be accomplished in many and various ways, that herein disclosed is regarded as a preferred form and as such has been illustrated in the accompanying drawings in which,

Figure 1 is a front elevation of so much 70 of a sewing machine of ordinary form as is necessary to disclose the application of this invention thereto;

Figure 2 is an elevation from the left 75 hand side of Fig. 1 on enlarged scale, showing applicant's invention as applied to the machine of Fig. 1;

Figure 3 is a top plan view of certain of 80 the mechanisms shown in Fig. 2, the upper part thereof being sectioned away for clearness of disclosure;

Figure 4 is a front to rear partial vertical section of the button receiving chamber forming a part of the mechanism; and

Figure 5 is a left hand elevation illustrating the movable gate for permitting the 85 discharge of buttons from the button receiver.

Referring to the drawings, 1 is the machine base and 2 the usual overhanging arm thereon, said arm carrying certain of the stitch forming instrumentalities including the needle bar 3 and the needle 4, all in the usual well known manner. The machine herein disclosed is of that type intended for 90 the sewing on of buttons and is provided with the usual mechanism for this purpose. Included in this mechanism is an oscillatory sector 5 to which oscillatory movements are 95 imparted in time with the machine and operating through connections of usual form and arrangement, an example of mechanism adaptable to such use being seen in the patent to Walrath, 528,832, Nov. 6, 1894. Extending to the left, as seen in Fig. 1 from 100 said sector is an adjustable link member 6

having its end connected to the button clamp mechanism hereinafter described.

As is common to machines of this character it is proposed to provide automatically 5 acting stop mechanism which will stop the machine at the completion of a predetermined number of stitches with the sector 5 always occupying the same angular position when the machine is stopped. It is 10 also proposed to employ a manually actuatable treadle for starting the machine at the beginning of each button attaching operation. Such devices being all old and well known in the art, it has been thought unnecessary 15 to describe them at length in this application.

At a point to the rear of the needle as respects the position of the operator and upon the bed plate of the machine or a suitable 20 bracket fixed thereto, is pivoted, as by means of a bolt 8, a supporting member 9, said supporting member having projecting up from its rear extremity a pair of ears or lugs, one of which is indicated at 10. Passing 25 through said lugs is a pivot pin 11 upon which is mounted to swing in a front to rear direction a block 12, said block having attached to its upper end a support 13 carrying the button clamp and the actuating devices therefor.

This button clamp is in general of ordinary construction and comprises briefly a pair of arms 14, 15 pivoted at 16, 17 respectively to the support 13, said arms being 30 normally forced toward each other into closing position by means of a spring such as indicated at 18. For the purpose of opening the clamp comprising the jaws 14 and 15 for releasing a button therefrom said 35 jaws are provided with downwardly extending pins 19, 20 respectively, said pins extending into inclined cam slots 21, 22, formed in a plate 23 slidable in a front to rear direction.

40 Below the support 13 and connected to one end of the plate 23 as shown in Fig. 3 is a rod or bar 24 slidably guided adjacent its rear end by means of a suitable bracket 25, said bar having projecting from its rear 45 extremity a lug 26, which is formed with a downwardly and forwardly inclined cam surface 27, see Fig. 2, for a purpose to be hereinafter described. The button clamp in addition to the movable jaws 14 and 15 comprises a fixed jaw 28 forming an abutment or stop whereby the button is prevented from excessive rearward movement as it is inserted between the movable jaws of the 50 clamp.

60 The support 13 is provided near its forward end with an upstanding boss 29 within which is secured a pivot pin 30 passing through an opening in the left hand extremity of the link 6 whereby upon oscillation of the sector 5 lateral movement is imparted

to the support 13 and with it the button clamp comprising the jaws 14, 15 and 28. Such movement reciprocates the button transversely beneath the needle whereby the latter is enabled alternately to pass through the eyes of the button in attaching it to the fabric which lies upon the bed plate of the machine and beneath the button clamp. 70

In order that the button clamp may serve 75 as a presser foot for holding the material in position during the attaching operation the support 13 is mounted to move in a vertical plane in swinging about the pivot pin 11, a spring 31 being provided which normally acts 80 to retain the button clamping presser foot in its lower or work-engaging position. Extending outwardly from the forward end of the support 13 or in any other convenient place is a staple 32 to which is connected the 85 lower end of a bar 33 by which the presser foot and button clamp may be raised at the will of the operator as occasion may require. 90

Fixed upon the front portion of the machine head is a bracket 34 having a depending arm 35 extending downwardly and to the left of the needle bar as seen in Fig. 1. The lower end of this arm 35 is provided with a laterally and horizontally disposed 95 portion 36 in which is formed a substantially horizontal guideway 38 which extends from front to rear transversely of the axis of the needle bar. Said portion 36 is also provided with a substantially cylindrical, 100 upwardly extending part, said part being tubular and forming a button receiving chamber 40. The left hand wall of said chamber as seen at 41 in Figs. 3 and 4 is somewhat higher than the right hand wall 105 thereof and the latter is provided with a vertical slot 42 for a purpose to be herein-after described.

Slidable within the guideway 38 is a member 43 constituting a button transerrer. 110 As herein shown that extremity of said transerrer which is directed toward the needle bar is provided with an extension 44 having its upper surface 45 substantially flat and arranged to support a button. To the rear of said surface 45, as respects the direction of advance of the latter toward the needle bar, is formed an upwardly extending shoulder 46, said shoulder as seen in Fig. 3 having a V-notch 47 therein. This 115 notch serves to center a button placed upon the supporting surface 45, the shoulder acting as an impelling element for moving the button toward the needle bar position as the slide 43 is so moved. At its extremity the extension 44 is provided with a notch 48 adapted to engage over the end of the stationary clamping jaw 28 whereby 120 to permit a button resting upon a surface 45 to firmly engage said jaw 28. To secure 125

proper operation of the device, a plurality of slides or transferer members 43 may be provided having extensions 44 of different heights whereby to support buttons of different thicknesses in proper relation to the clamping devices.

The opposite sides of the extension 44 are provided with vertically extending notches 49 forming passages through which project a pair of prongs or fingers 50 carried by a resilient member illustrated as a flat spring 51 attached as by means of a screw 52 to the lower surface of the slide 43. As thus arranged the prongs or fingers 50 may extend through the eyes of a button lying upon the surface 45 and thus prevent any angular movement of rotation of the button about its center while so positioned. On that extremity of the bar 43 which lies nearest the operator is pivotally secured the end of a slide bar 53 which as clearly indicated in Fig. 3 extends to the rear of the machine where it is guided in suitable supports 54 and 55. The supports 54 and 55 may if desired be carried by a bracket 56 secured to the base plate of the machine, this arrangement, however, not being an essential part of the invention. Between the forward extremity of the bearing member 55 and a collar 57 fixed upon the rod 53 is a spring 58, said spring serving normally to maintain the slide 43 in its position nearest the operator as shown in Fig. 3. An adjustable block 59 is secured to the rod 53, as by means of a set screw 60, and has formed upon its left hand portion a downwardly and forwardly inclined cam surface 61, the purpose of which will be hereinafter described.

For the purpose of feeding buttons in succession to the button receiver or chamber 40, the machine, in accordance with the present invention, is supplied with the removable supporting reservoir shown more particularly in Figs. 1 and 5. At the right hand upper portion of the machine head is provided a forwardly extending boss 62 having a substantially flat forward surface in which is a slot or groove 63 therein. 64 is a cover plate adapted to be secured to the forward surface of the boss 62 as by means of a screw 65 or other suitable removable connection. The button reservoir comprises a filamentous element adapted to be passed through the eyes of buttons to be strung thereon, said element as herein shown consisting of a suitable rod or wire 66 preferably of resilient material such as spring steel. This wire or rod has its central and main portion substantially straight but is bent at its extremities to provide oppositely directed portions 67, 68 respectively, the portion 67 being arranged to be received within the slot 63 and to be securely retained in position therein by means of the cover plate 64. The reversely curved down-

wardly extending portion 68 of the reservoir wire is arranged to be positioned within the button receiving chamber 40, the slot 42 in said reservoir serving to facilitate the positioning of the end 68 therein. The length of the wire member 66 and the angularity of the extremity 68 are such that the downwardly directed tip of the wire is normally located substantially in alignment with the left hand upwardly extending prong or finger 49 and terminates at a distance above the same slightly in excess of the thickness of the buttons to be employed.

As will be noted from Fig. 1 the central portion of the wire 66 extends in a downwardly inclined direction to the left and toward the receiver 40. For supporting the reservoir wire 66 at its free left hand extremity, the forward face of the arm 2 is provided with a bracket member 69 provided with forwardly extending lugs 70, 71, having guiding openings therein through which passes a vertically arranged bar or rod 72. The bar or rod 72 has fixed thereon, at a point between the lugs, a collar 73 and between said collar and the opposite lug is mounted a compression spring 74, said spring serving normally to hold said bar or rod 72 at its upper limit of movement. The bar or rod 72 at its lower end supports a downwardly extending hook like member 75, which is provided with a notch 76 for engagement with the wire 66 from beneath, whereby to support the latter. Above the notch 76 the hook member 75 is provided with a recess or opening 77. The upper end of the bar or rod 72 carries a disk 78 whereby the operator may depress the rod or bar 72 to bring recess 77 into central alignment with the reservoir wire. A series of buttons 79 is shown as strung upon the reservoir wire 66, the left hand button of the series resting against the lateral surface of the hook member 75 which thus serves as an abutment to prevent downward sliding of buttons along the wire. The opening 77 above the notch 76 is of such extent as that when the rod or bar 72 is depressed as above noted and said opening is brought into central alignment with the wire 66, buttons are free to pass downwardly along the wire through the opening or recess 77. The end of the hook member beyond the notch 76 may be beveled as indicated at 75a so as to readily enter between buttons of the series in returning to its normal position. The rod or bar 72 with the parts supported thereby thus constitutes a support for the button reservoir and a movable gate or retainer for permitting the discharge of buttons toward the terminal end of said reservoir.

80, 81 indicate a pair of lugs fixed to the head of the machine, said lugs providing aligned vertical openings in which is slidably guided a bar or rod 82. The bar or rod

82 has its upper end bent angularly as shown at 83 to provide a substantially horizontal surface 84 the rearward extremity of said angular portion being downwardly bent whereby to form a portion 85 of arcuate form. To the lower extremity of the rod or bar 82 is connected the upper end of the link 33 hereinbefore referred to. Mounted in suitable bearings formed in a lug 86 projecting rearwardly from the machine head is a stub shaft 87 having fixed thereon a crank arm 88 whose extremity 89 is formed to engage the surfaces 84 and 85 of the rod or bar 82, said surface 85 having a curvature substantially that of the circle struck out by said extremity 89 of arm 88 about the center of shaft 87. Fixed to the stub shaft 87 is a rearwardly and upwardly extending arm 90, said arm being engaged by a spring 91 secured to a fixed portion of the machine frame and serving normally to retain the arm 90 in its uppermost position as shown in Fig. 2. To the free extremity of the arm 90 is connected a member 91 leading to a suitable treadle of ordinary form preferably that employed for starting the machine.

At an intermediate point 92 of the arm 90 is connected the upper end of a vertically movable rod 93, said rod being suitably guided in its movements and having fixed thereon a block 94 adjustable thereon by means of a set screw 95 or in any other suitable manner. On its right hand face as viewed by the operator, the block 94 is provided with a downwardly and forwardly inclined cam surface 96, said surface and the cam surface 61 carried by the block 59 secured to rod 53 intersecting the same vertical plane. To the left hand face of the block 94 is pivoted, by means of a screw 97 or other suitable device, a cam carrying member 98 herein shown as a substantially flat plate provided at its lower side with a laterally extending forwardly and downwardly inclined cam surface 99. 100 is a stop pin serving to limit swinging of said member 98 in a forward direction about the screw 97, said member 98 being held normally in contact with said pin 100 by means of a suitable spring 101. As seen in Fig. 2 the cam surface 99 lies at a point substantially below the cam surface 96.

The operation of the machine hereinbefore described is substantially as follows, it being understood that the needle is actuated in the usual manner together with the other stitch forming instrumentalities and that the button holding clamp is oscillated in time with the stitch forming mechanism.

Supposing that the machine has just completed the attaching of a button to the fabric and that the parts are in the position in Fig. 2 with the machine stopped, the operator places his foot upon the treadle member thereby, through the connection 91,

swinging the member 90 downwardly about the center of shaft 87, moving the end 89 of the arm 88 in an upwardly directed arc. During the first portion of such movement the surface 89 acting against surface 84 operates to lift the bar or rod 82 and through the connections described lifting the button clamping presser foot away from the bed plate until the clamping members lie substantially in the horizontal plane of the guideway 38 and of the transerrer bar 43. Upon reaching this position the movement of surface 89 into contact with the arcuate surface 85 serves to determine the upward movement of bar 82 and at the same time to lock the same in its elevated position during the succeeding portion of the movement of the arm 90. As the operator continues to depress the treadle the rod 93 moves downwardly until the cam member 99 is brought into contact with the cam surface 27 carried by slide 24. Further movement operates to cam said slide 24 rearwardly, thereby releasing the clamping arms 14, 15 to drop the button therefrom. As the cam surface 99 is of relatively short extent it quickly passes out of contact with the surface 27 whereupon the clamping jaws are immediately closed by their actuating spring 18. Further movement downwardly of the rod 93 now brings cam 96 into contact with the cam surface 61 whereby slide bar 53 is moved rearwardly. Such movement is completed while the cam surfaces 96 and 61 remain in contact.

During such movement of the bar 53 it being assumed that a button has been placed in the receiver 40 and that such button rests upon the surface 45, with the prongs or fingers 50 extending upwardly through its eyes and with its edge engaged by the notched shoulder 46, travel of the transerrer 43 toward the needle position will carry the button from within said receiving chamber until the rim or edge of the button strikes the forward extremity of the clamping jaws 14, 15. As the transerrer now continues to move, the button, impelled forward by the shoulder 46, serves to cam apart the jaws 14, 15, the movement of the transerrer 43 continuing until the button is brought into engagement with the fixed jaw 28. As soon as this has been accomplished the operator releases the treadle, whereupon the rod 93 rises. The first effect of this is to release the pressure between cams 96 and 61 permitting spring 58 to restore the button transerrer to normal position. As the cam 99 moves upwardly it again engages the lug 26 but as the member 98 is free to swing about the pivot 97 in a rearward direction the cam 99 moves idly past the lug 26 without further actuating the clamp opening slide. During the movement of the member 93 the arm 88 swings

downwardly and forwardly and after the completion of the above operations permits the button clamping presser foot to resume its normal position resting upon the fabric.

5 Preferably in accordance with usual practice although not forming any part of the present invention the completion of the treadle movement serves to start the machine into operation, thus saving the time of the operator.

As the buttons are successively moved into attaching position by the transerrer, additional buttons are permitted to slide down the inclined reservoir wire one by one, 15 the operator actuating the rod or bar 72 with its button discharging gate at the necessary intervals. In operation the resiliency of the reservoir wire 66 permits it to vibrate readily under the jar of the machine 20 whereby the buttons are caused to flow freely and readily from the upper end of the reservoir toward its discharge end. It will furthermore be clear that the reservoir 25 66 is readily removable from the machine by detaching the cover plate 64 and that a series of such reservoirs filled with buttons may be kept in stock, to be applied to the machine in succession as the buttons thereon are exhausted.

30 When a reservoir wire having buttons strung thereon is applied to the machine, the buttons, by reason of the fact that they are suspended above their centers of gravity, automatically orient themselves into like 35 positions with their eyes in vertical alignment, and throughout their movement along the reservoir wire gravity thus serves to maintain the buttons in the position which they first assume. As the buttons pass down 40 the extremity 68 of the wire they are prevented from becoming angularly displaced by contact with the upwardly extending left hand wall 41 of the button receiver and are thus caused to drop upon the supporting 45 surface 45 in properly oriented position for the ready engagement with their eyes of both the prongs 50. The button supply reservoir thus serves in an extremely simple and efficacious manner automatically 50 to orient all buttons mounted thereon into proper position and to maintain them in such position throughout their travel toward the receiving devices, thereby avoiding any necessity on the part of the operator for 55 using care in locating the buttons within the clamp, or the employment of complicated and mechanically actuated devices for accomplishing such a result.

60 While in the foregoing description the reference has been made to the feeding and attaching of buttons the term "button" has been used in a generic sense only and is intended to include any and every form of fastener capable of use therein.

65 Having described a preferred form of the

invention, and the mode of operation of the same, what I claim and desire to secure by Letters Patent of the United States is:

1. A reservoir for use in fastener attaching machines comprising in combination a 70 resilient member constructed and arranged to pass through an opening in a fastener whereby to pendants support the same, and means for holding said member in downwardly inclined position and with its lower 75 end free.

2. In a button sewing machine in combination a button reservoir comprising a filamentous member inclined downwardly at an acute angle to the horizontal and constructed 80 and arranged to constitute the sole support for buttons strung thereon, and means for detachably supporting said reservoir in operative, button delivering position.

3. A reservoir for use in button sewing machines comprising a resilient member constructed and arranged to pass through the eye of a button and to constitute the sole support for the button and means engaging one extremity of said member for supporting it in inclined position at an acute angle to the horizontal and with its lower 90 end free.

4. In an attachment for button sewing machines, in combination a member constructed and arranged to be threaded through the eye of a button and devices for detachably supporting said member in a position slightly inclined to the horizontal. 95

5. In a device of the class described, in combination stitch forming instrumentalities and means for feeding buttons thereto in succession, said means comprising a detachable reservoir constructed and arranged automatically to similarly orient all buttons 100 supported thereby when secured in operative position.

6. In a device of the class described in combination, a length of wire having a substantially straight central portion and a 110 downwardly curved terminal portion, and means engaging the upper extremity of said wire for detachably securing the same in operative position.

7. A button reservoir comprising in combination a length of filamentous material having its major central portion substantially straight and its extremities curved in opposite directions respectively, and means engaging one of said extremities whereby to support said length of material with its straight portion inclined to the horizontal. 115

8. A fastener setting machine having in combination, a frame member provided with a groove comprising angularly disposed portions therein, a fastener reservoir having elements arranged to be received in the respective portions of said groove, and a removable cover plate for securing said element in operative position within said groove. 125 130

9. A button reservoir for button sewing machines comprising means for supportingly engaging a series of buttons at points above their respective centers of gravity, 5 and means for regulating discharge of buttons from said reservoir.

10. A reservoir for fasteners comprising in combination, a filamentous support upon which said fasteners may be successively 10 strung and whereby they are supported, and a gate member movable transversely of said support and provided with an aperture for the passage of fasteners.

11. In a fastener attaching machine, in 15 combination attaching instrumentalities, and a reservoir for fasteners, said reservoir comprising a downwardly inclined element upon which individual fasteners may be strung, means for supporting said element adjacent 20 one extremity, and movable means for supporting said element at a point spaced from said first means, said movable means being constructed and arranged to determine the discharge of fasteners from said reservoir.

25. 12. In a device of the class described in combination with a reservoir for fasteners comprising a filamentous element upon which the fasteners may be supported, means fixedly engaging said element adjacent one 30 extremity, and a slidable member having a part constructed and arranged normally to supportingly engage said element at an intermediate point in its length, said member being provided with a fastener delivering 35 opening.

40. 13. In a device of the class described, in combination with a rod-like fastener reservoir, a gate member cooperating with the same, said gate member comprising an element normally spring actuated to contact with said reservoir and serving to block the passage of fasteners therealong, said element being provided with a fastener discharge opening therein.

45. 14. In an attachment of the class described, in combination, an inclined, rod-like member upon which fasteners may be hung, and a gate therefor, said gate comprising a slide having a notched portion serving to engage said member, spring means normally maintaining said notched portion in engagement with said member, said slide being provided with an opening adjacent said notched portion, and means whereby said 55 slide may be moved in opposition to the spring whereby to position said opening for the passage of fasteners therethrough.

60. 15. In combination in a fastener attaching machine, a fastener reservoir constructed and arranged to deliver fasteners successively and in definite position of orientation, a receiver comprising a chamber for fasteners delivered from said reservoir said chamber being of a cross section similar to the 65 peripheral contour of a fastener, and a

transferring device associated with said receiver and arranged to convey successive fasteners therefrom to the point of use.

16. In a button attaching mechanism, in 70 combination a button reservoir comprising an element constructed and arranged to deliver buttons successively and in definitely oriented position and a button receiver comprising a tubular chamber, associated with said element and arranged to receive 75 and guide buttons in their discharge from the reservoir.

17. In a fastener attaching machine, in 80 combination, fastener clamping and fastener attaching means, a fastener receiver comprising an open ended tubular member, a transerrer movable transversely across one end of said receiver, and means movable with said transerrer constructed and arranged to engage the fastener positively and to prevent any angular displacement of the latter relatively to the transerrer.

18. In combination with fastener attaching instrumentalities including a fastener retaining clamp, a fastener receiving receptacle, and a transerrer for conveying fasteners from said receptacle to said clamp, said transerrer comprising a slide member movable across the end of said receptacle, and having a fastener supporting element, 95 a fastener impelling element, and means for preventing angular movement of a fastener relatively to the supporting element.

19. In a fastener attaching machine, in 100 combination, a fastener retaining clamp provided with normally closed jaws, fastener presenting means and a transerrer constructed and arranged to receive a fastener delivered by said presenting means and forcibly to insert it between the jaws of said clamp said transerrer comprising means for positively preventing angular movement of the fastener during its insertion between said jaw.

20. In combination in a button sewing machine, a button receiving chamber, a button positioning clamp provided with relatively movable jaws, spring means normally retaining said jaws in closed position, and a transerrer constructed and arranged to receive a button from said chamber and to thrust said button forcibly into contact with said clamping jaws whereby the edge of the button serves to cam open the jaws to receive the button between them, said transerrer comprising means for positively preventing angular movement of the button during its insertion between said jaws.

21. In a device of the class described, in 125 combination, a fastener transerrer comprising a slide member having a forwardly extending fastener supporting surface, a spring member mounted upon said transerrer adjacent said surface, and a plurality of fastener engaging fingers carried by said 130

spring member and extending outwardly from said surface.

22. In a button attaching machine, in combination, a button transferring mechanism comprising a slide member having a forwardly directed extension providing a button support, said extension being of less vertical thickness than the main portion of the slide, said slide having a notched button-impelling shoulder at its junction with the extension and said extension having a vertically arranged slot in its extremity.

23. In a button attaching machine, button attaching devices, a button delivering device, and a transferrer for conveying buttons from the latter to the former, said transerrer comprising means for positively preventing angular movement of the button during its transference from the delivering 20 to the attaching devices, means normally operative to retain said transerrer in position to receive a button from said delivering device, and a cam member for moving said transerrer toward said attaching devices.

24. A button sewing machine having in combination stitch forming devices and a button retaining clamp, a button delivering device, and a transerrer slidable in a direction to convey a button from said device to the clamp, said transerrer comprising means for positively restraining the button against angular movement, a spring actuated slide normally operative to hold said transerrer in button receiving position, and a treadle actuated cam movable transversely of said slide and constructed and arranged to engage an element of said slide whereby to move the transerrer toward said clamp.

25. A button attaching machine comprising in combination a movable button clamp having spring closed jaws constructed and arranged to engage the edges of a flat button and means whereby the jaws may be opened, and devices for actuating said jaw opening means comprising a reciprocable cam movable relatively to an element of said opening means for actuating the latter, said cam being operative to actuate said means in one direction of movement only.

26. In combination in a button attaching mechanism, a button clamp comprising relatively movable jaws, spring means for closing said jaws, a slide plate for opening said jaws, said plate having an actuating lug, and a pivotally supported member movable transversely of the path of said plate, said member having a cam element for engaging said lug whereby to actuate said slide.

27. In a fastener attaching machine in combination, a fastener retaining clamp comprising relatively movable jaws, spring means operative normally to close said jaws, and an element constructed and arranged, upon continued movement in the same direction, momentarily to open said jaws and

immediately to release them to close under action of said spring means.

28. A button attaching mechanism comprising in combination a pair of spring closed jaws, a slidable member for opening said jaws, and an element reciprocable transversely of the movement of said slide and provided with a cam, said cam being constructed and arranged operatively to engage said slide whereby to open said jaws when reciprocated in one direction, and to slip idly past said slide in its return movement.

29. In a machine of the class described, in combination, a button clamp having movable jaws, a slide for controlling the movement of said jaws, a movable button transerrer for conveying a button to said jaws, a slide for controlling said transerrer, a cam engaging lug carried by each of said slides, and a pair of cams simultaneously movable transversely of the direction of movement of said slides and constructed and arranged to engage the respective lugs whereby first to actuate the jaw controlling slide and thereafter to actuate the transerrer slide.

30. In a button attaching mechanism in combination, a button clamp comprising normally closed jaws, a button transerrer, and treadle actuated means comprising cam elements constructed and arranged successively to open said clamp and actuate the transerrer.

31. In a button sewing machine in combination, stitch forming instrumentalities and a work support, a button clamp movable toward and from said support and serving as a presser foot, means normally maintaining the clamp in button retaining position, means for opening the clamp, and treadle actuated connections operative in succession to raise the button clamping presser foot, to maintain it in elevated position and to open the clamp.

32. A fastener attaching mechanism having in combination attaching instrumentalities, a movable clamp device for retaining a fastener in attaching position, a transerrer for inserting a fastener within said clamp, and means constructed and arranged successively to move the clamp to receiving position, to open the clamp to release a fastener therein, to close the clamp, and to actuate the transerrer to insert a fresh fastener in the clamp.

33. A button attaching mechanism having in combination, a vertically movable button clamp, means normally acting to maintain said clamp in depressed position, a button transerrer mounted in a plane above the normal plane of said clamp, a vertically slidable member having connection with said clamp and provided with an angularly disposed arm provided with an arcuate por-

tion, an element movable in an arc and arranged for contact with said arm, and means for moving said element whereby first to lift said slidable member to position the clamp in the plane of the transerrer and then to maintain said clamp in such position for an appreciable length of time.

34. In a button sewing machine, the combination with the button holder, of a button magazine, a feed device operative to receive buttons from said magazine and deliver the

same to the holder, said feed device having means for holding the buttons in predetermined position thereon and the magazine having means for delivering the buttons to the feed device in such predetermined position, and operating means for the feed device.

Signed by me at Boston, Massachusetts, this fifteenth day of May, 1920.
